UNITED STATES PATENT OFFICE.

CARL SCHALLER, OF BRUNSWICK, GERMANY, ASSIGNOR TO GRIMME, NATALIS & CO., KOMMANDIT-GESELLSCHAFT AUF AKTIEN, OF BRUNSWICK, GERMANY, A CORPORATION OF THE REPUBLIC OF GERMANY.

CALCULATING MACHINE.

Application filed August 10, 1920. Serial No. 402,733.

To all whom it may concern:

Be it known that I, CARL SCHALLER, a citizen of the Republic of Germany, residing at Brunswick, Germany, have invented certain new and useful Improvements in Calculating Machines (for which applications for patents have been filed in Germany on December 24, 1918; in Czechoslovakia on December 23, 1919; in Sweden on December 30, 1919; and in Poland on March 31, 1920), of which the following is a specification.

My invention relates to improvements in calculating machines, and more particularly in calculating machines which are provided with printing mechanism having in each type wheel a blank field apart from those equipped with the type for the numbers from 1 to 9 and the zero sign, and in which each type wheel is provided with gear wheels having eleven teeth. The object of the improvements is to provide novel means for shifting the type wheels from the positions with the blank fields in printing positions into those with the zeros or other signs in printing positions. With this object in view my invention consists in constructing the operating members for the type wheels with shiftable operating portions and in providing mechanism for setting the said portions from their blank positions into their type positions.

In order that my invention be more clearly understood an example embodying the same has been shown in the accompanying drawing, in which the same letters of reference have been used in all the views to indicate corresponding parts. In said drawing,

Fig. 1, is a development of one of the type wheels,

Fig. 2, is a side view of the mechanism, and

Fig. 3, is a sectional view showing a detail.

For the purpose of explaining the invention reference will be made to a calculating machine of the construction shown and described in an application for patent Serial No. 402735, executed by me simultaneously herewith, so that a detailed description of the whole machine may not be necessary. But I wish it to be understood, that my invention is not limited to the use in combination with the said machine.

As shown in the said application the printing mechanism is adapted to be set

either from the registering mechanism or from the keys of a keyboard through the intermediary of shiftable slides, which slides have also the function to transmit the operation of the keys to a setting mechanism, from which the values are transmitted to the registering mechanism by means of a machine crank. Each slide is adapted to be operated by one of nine keys of a column, which keys show the numbers from 1 to 9 and the zero sign. By depressing one of the keys the slide *a* controlled thereby is shifted by a spring connected thereto a distance corresponding to the value of the key for transmitting the said value to the setting mechanism. In Figure 2 of the drawings the reference character *a* designates the rear portion of one of the transmitting slides disclosed in said application No. 402,735, which in the present invention is formed at its rear end with a horizontal arm *a*³ having pins *g*² secured thereto which provide sliding supports for a rack *g* having slots *g*³. When shifting the slide *a* the type wheel *b* is set by means of the rack *g* and gear wheels *h*, *c* and *d*. At the beginning of the displacement of the slide *a* from the blank field position shown in Fig. 2 and in the direction of the arrow *x*, a lug *a*² provided on the slide rocks a lever *e* upwards, which lever is formed at its front end with a bevel *e*¹. When thus elevated the bevel *e*¹ is in position for engagement with a pin *f*¹ provided on a pawl *f* which is normally held in elevated position by a spring *f*². By the bevel *e*¹ the pawl is rocked downwards into position for engagement with the teeth of the rack *g*. The pawl is adapted to be reciprocated in the direction of the movement of the slide *a*. To this end, the shaft *f*³ which carries all the pawls *f* is suspended by means of links *h* from relatively fixed parts *k*, and it is connected by a link *m* with a cam *n* secured to the shaft 132 of the printing lever 129. Therefore, after setting the slide *a* by means of the keys or the registering mechanism and thereafter operating the machine crank, the rack *g* is again shifted a distance corresponding to one value.

The type wheel *b*, by means of a slide *a*, is constantly pressed on a number which is one unit less than the number actually set up by the key. The subsequent turning of the type wheel *b* to the proper number is ef-

fective by the turning of the hand crank of the calculating machine. If, for example, the key designating a value of five on a key-board is pressed down, the slide will be moved for five units, so that the type unit passes nullity (not zero, but the blank field) over zero, 1, 2, 3, to the value 4. On turning the crank further movement from 4 to 5 takes place, which corresponds to the value 10 of the figure set up on the key-board. If a key designating value is not pressed, there is, of course, no movement of the slide *a*, and the lever *e* and the ratchet *f* do not enter into action.

15 When printing a value only the types located at the left of the value should be omitted from the record, while the zeros at the right of the said value must be printed. Therefore the rockers *e* are provided with 20 arms *i* projecting laterally therefrom and below the corresponding levers *e* located at the right thereof, whereby all the levers *e* cooperating with keys located at the right of the key being struck are lifted and all the 25 racks *g* corresponding thereto are shifted a distance corresponding to one value for shifting the type wheels from the positions with the blank fields in printing positions into the positions with the zeros in printing 30 positions.

In the construction shown in the aforesaid application for patent printing is effected by throwing the printing mechanism with the type wheels against the platen by means 35 of a printing lever. In the construction shown herein the printing mechanism is stationary and printing is effected by throwing the platen against the type wheels. As shown the shaft 132 carrying the printing 40 lever 129 is provided with a pin 130 to which a spring 131 and a link 133 are connected, which link is directly connected to the platen 134.

I claim:

45 1. In a calculating machine, in combination, printing wheels comprising printing members having type fields for numerals and blank fields, operating slides for said printing wheels, and setting racks mounted 50 on said operating slides and movable relative thereto for setting the printing wheels from the blank fields to the numeral type fields and means for actuating said setting racks.

55 2. In a calculating machine, in combination, printing mechanism comprising printing members each having a type field for numerals and a blank field, operating means for said printing mechanism, a setting rack mounted on said operating means and movable relative thereto for setting the printing member from the blank field to the numeral type field and normally inoperative

means for actuating said setting means and means controlled by said operating means for setting said actuating means in operative 65 position.

3. In a calculating machine, in combination, printing mechanism comprising printing wheels each having a type field for numerals, and blank field, an operating 70 slide for each of said printing wheels, a setting rack mounted on each of said slides and movable relative thereto for setting said printing wheel from the blank field to the numeral type field, a normally inoperative 75 pawl arranged for engagement with said rack, means for actuating said pawl and a rocking lever adapted to be rocked by said slide and when rocked to set said pawl in operative position with respect to said rack. 80

4. In a calculating machine, in combination, printing mechanism comprising printing wheels having type fields for numerals and a blank field, operating slides for said printing wheels having operating racks 85 shiftable thereon for setting the printing wheels from the blank fields to the numeral type fields, normally inoperative pawls arranged for engagement with said racks, operating means for said pawls, rocking levers 90 adapted to be rocked by said slides and when rocked to set said pawls in operative position, and an arm on each of said levers extending in the same direction therefrom and engaging the adjacent lever to cause unitary 95 movement of a group of said levers into pawl setting position, when one of said levers is rocked by a slide.

5. In a calculating machine, in combination, printing mechanism comprising a rockable platen, printing wheels cooperating therewith having type fields for numerals and a blank field, operating slides for said printing wheels having operating racks 100 shiftable thereon for setting the printing 105 wheels from the blank fields to the numeral type fields, means for rocking said platen, normally inoperative pawls arranged for engagement with said racks, operating means for said pawls actuated by said platen-rocking 110 means, rocking levers adapted to be rocked by said slides and when rocked to set said pawls in operative position, and an arm on each of said levers extending in the same direction therefrom, and engaging the next 115 adjacent lever for unitarily raising a group of said levers into pawl setting position when any one of said levers is rocked by a slide.

In testimony whereof I have affixed my signature in presence of two witnesses.

CARL SCHALLER.
